MULTIPLE SUSPENSION FILE

Frank D. Jonas, East Williston, N. Y., assignor to
 Oxford Filing Supply Co., Brooklyn, N. Y., a
 partnership comprising Richard A. Jonas,
 Richard A. Jonas, Jr., Robert P. Jonas, Frank
 D. Jonas, and Edward F. Jonas

Application October 8, 1941, Serial No. 414,063

4 Claims. (Cl. 129—16.7)

This invention relates to improvements in filing devices of the suspension type, and more particularly with what may be termed multiple suspension files in which a plurality of individual suspension files are coupled together in accordion-like manner.

The general object of this invention is to provide a new and simplified arrangement by means of which a plurality of suspension file pockets or folders may be operatively connected by means of the suspension bars to form a multiple suspension file.

Another object of this invention is the provision of a simplified construction for detachably securing index tabs to the individual pockets of such file.

Other and more detailed objects of the invention will be apparent from the following disclosure when taken in connection with the attached drawing.

This invention resides substantially in the combination, construction, arrangement and relative location of parts, all as will be described in detail below.

In the accompanying drawing,

Figure 1 is a single line perspective of one construction in accordance with this invention;

Figure 2 is an end elevational detailed view of a modification in accordance with this invention.

As illustrated in the drawing, and as is known in the art, suspension files comprise pockets formed of folded suitable fibrous material in which data sheets may be kept and which files are supported by suspension from rails in filing cabinets. In this art such suspension filing folders are used both singly and in multiple and it is an object of this invention to provide an improved form of construction with relation to the multiple suspension files.

There is illustrated in Figure 1 two individual suspension files connected together to form a multiple file, and it will be understood of course that the number of individual pockets in such a file may be multiplied as desired in accordance with the structure of this invention.

The first of the file pockets is shown as formed by a rear wall 10 and a front wall 11 resulting from the folding along the fold line 12 of a sheet of suitable fibrous material. The upper edge of the rear wall 10 is folded downwardly and inwardly along the fold line 13 to form a flap 14 which is glued down against the inner face of the rear wall to form a passage into which the suspension bars 15 may be slid endwise.

The flap 14 is provided with a series of transversely spaced slots 16 therethrough by means of which an index tab 17 may be mounted at any one of a plurality of transversely spaced points. 5 The index tab 17 may be of any suitable construction, and has been illustrated in the form shown for the purpose of description without intention to be limited thereto. This index tab consists of a body of suitable material comprising a portion 18 and an offset inclined rearwardly extending portion 19 upon which the index data may be directly recorded. Of course the index tab may be constructed in a multitude of known forms, as for example the type comprising 15 a transparent casing into which a data slip may be passed. The lower portion 18 of the index tab is provided with transverse wings 20 which are slipped into a pair of adjacent slots 16 to removably attach the tab at the desired point, as clearly illustrated in Figure 1.

The upper edge of the front wall 11 is folded downwardly and inwardly along the line 21 to form a flap 22 which is glued to the inner face of the front wall 11 to form a passage for the 25 suspension bar, as in the previous case. In this instance, however, the double plies thus formed are cut away at spaced intervals so as to leave a series of interrupted or spaced projections 23 all of which are aligned as is apparent, so as to 30 form an interrupted passage to receive a suspension rod.

The second filing folder of the unit is generally 35 similar to the one previously described and consists of a rear wall 24 and a front wall 25 resulting from folding a sheet of suitable material along the transverse substantially medial fold line 26. The upper edge of the rear wall 24 is folded downwardly and inwardly along the line 27 to form a flap 28 which is glued in place so as to form 40 a continuous passage between the plies, as previously described.

In this case also spaced portions of the upper edge are cut away to form notches 29, leaving the spaced projections 30 which are aligned to 45 form the interrupted passage for the suspension bar as before. It will be noted that the projections of the front wall 11 are staggered with respect to the projections of the rear wall 24 so that they all line up when the projections 23 lie 50 in the notches 29 to again form a substantially continuous channel into which the suspension bar 31 is slid endwise to lock these two walls together along their top edges.

The projections 30 are provided with a plurality of slots 32 formed at the upper portion of

the flap 28 to again provide detachable supports for an index tab. The index tab for the second filing folder is shown at 33 and, as before, consists of the connected portions 34 and 35 arranged so that the portion 35 inclines upwardly and rearwardly to provide a data space.

The portion 34 is provided with transverse wings 36 which may be slipped into a pair of the slots 32 to detachably mount the index tab 33 at any desired point transversely of the structure. With this arrangement, as is clear from Figure 1, the various index tabs 17 and 33 may be staggered so as to render them fully visible.

The upper edge of the front wall 24 is folded inwardly and downwardly along the fold line 37 to form the flap 38 which is glued to the inner face of the front wall 25 to form a passage in which the front suspension bar 39 may be slid endwise. This multiple filing folder can readily be supported on a pair of parallel rods at the side of the cabinet drawer in accordance with the usual practice.

It will be noted from Figure 1 that the rearmost wall 18 and the frontmost wall 25 are not notched, but if desired in order to make the individual file pockets universally available for coupling into any desired combinations they may be notched as in the case of the walls 11 and 24 so that any file folder may be coupled to any other file folder in the same manner to provide as many pockets as desired.

The structure of Figure 1 merely illustrates the finished effect that may be produced in the event that a multiple file of a known and available number of pockets is desired. Individual suspension file pockets of this type may be coupled together into multiple structures in other ways. A simple arrangement is illustrated in Figure 2 where an end elevational view of a pair of coupled walls such as the walls 11 and 24 is shown. Similar reference numerals are used for the same parts and it will be seen from Figure 2 how the suspension rod channels are formed by folding and gluing, as previously described. In order to couple these walls together by a modified construction spring clip channel members 40 may be slipped endwise over the upper contiguous channeled edges of the walls 11 and 24 to secure them together in a manner functionally similar to that accomplished by the construction of Figure 1. The clip 40 may be of sufficient length to coincide with the transverse width of the file folders or several clips of shorter length may be

distributed transversely of the width of the file folders to clip them together at spaced points.

Those skilled in the art will readily appreciate that other modifications of this invention will occur and I do not, therefore, desire to be strictly limited to the description as given for purposes of illustration, but rather to the scope of the claims granted me.

What is claimed is:

1. In a multiple suspension file of the type described the combination comprising a plurality of file pockets formed by connected front and rear walls, each of said walls being folded and formed to provide spaced sleeves, and suspension bars lying in said sleeves, said suspension bars except the first and last lying in the sleeves of adjacent pairs of file pockets to lock them together.

2. In a multiple suspension file, the combination comprising a plurality of file folders each including a front and rear wall, the upper edges of the walls of each file being formed to provide longitudinally spaced sleeves, suspension bars mounted in said sleeves, and means for securing said files together to form an accordion-like structure comprising said bars threaded through the sleeves of adjacent folders and projecting beyond the sides of the folders to form suspension supports.

3. A multiple filing folder of the type described, comprising a plurality of file folders each including a front wall and a rear wall, the upper edges of each of said walls being folded into double plies to form passages, the double plies of adjacent walls being complementarily notched to form spaced projections aligned with the projections of an adjacent wall, and suspension bars mounted in the passages thus formed to lock the folders together in series.

4. A multiple filing folder of the type described, comprising a plurality of file folders each including a front wall and a rear wall, the upper edges of each of said walls being folded into double plies to form sleeves, the double plies of adjacent walls being complementarily notched, suspension bars mounted in said sleeves, all of said suspension bars except the first and last being mounted in the sleeves of two folders to lock adjacent folders together, the first ply of one wall of each file having a plurality of slots, and removable index tabs mounted in said slots.

FRANK D. JONAS.
